GEORGE EDMUND DONISTHORPE, OF LEEDS, ENGLAND.

Letters Patent No. 76,417, dated April 7, 1868; patented in England, October 28, 1863.

IMPROVED COAL-MINING MACHINE.

The Schedule referred to in these Letters Patent and making part of the same.

TO ALL TO WHOM IT MAY CONCERN:

Be it known that I, GEORGE EDMUND DONISTHORPE, of Leeds, in the county of York, England, a subject of the Queen of Great Britain, have invented or discovered new and useful "Improvements in Apparatus used when Getting Coal and other Minerals;" and I, the said GEORGE EDMUND DONISTHORPE, do hereby declare the nature of the said invention, and in what manner the same is to be performed, to be particularly described and ascertained in and by the following statement thereof; that is to say—

This invention has for its object improvements in apparatus used when getting coal and other minerals. For this purpose carriages running on rail or tramways, and having picks or cutting-tools, worked by power, are sometimes now employed. Now, according to my invention, in order to steady such carriages on the rails, whilst the picks or cutting-tools are in action, I employ wedges on the sides of the rails, such wedges entering between the rail and the frame of the carriage, or a projection therefrom. The wedges are drawn in by means of springs, each tending constantly to draw its wedges into the space between the side of the rail and the frame of the carriage, or the projection thereon. In this way the carriage is firmly secured to the rails, so as to prevent any lateral motion. The wedges do not, however, interfere with the forward motion of the carriage, the smaller ends of the wedges being towards the front of the carriage; consequently, the carriage, in advancing, immediately clears itself from them.

My invention also consists in employing, in apparatus for getting coal and other minerals, a clearer, in combination with the pick, the clearer being so arranged that, at each stroke of the pick, it enters with it into the groove cut in the coal or mineral, and, as the pick returns, the clearer retires with it, raking out, as it does so, the "small" behind the pick. The point of the clearer, in entering, is some distance behind the point of the pick, but, when the latter comes to the end of its forward motion, the point of the clearer comes up to the point of the pick, and the two enclose the small coal or mineral between them. In retiring, the clearer and pick remain with their points close together, and they carry with them, out of the groove in the work, the "small" previously enclosed; and, in order that my invention may be most fully understood and readily carried into practice, I will proceed to describe the accompanying drawings.

Description of the Drawings.

Figure 1 shows a plan of so much of a machine for getting coal and other minerals as is necessary for illustrating my invention.

a a and *b b* are the wedges for steadyng the machine at the time that the picks or cutting-tools are in action. These wedges enter between the projections *d¹ d¹*, on the frame of the carriage *d*, and the rails *c c*, on which the carriage is supported. The projecting parts *d¹ d¹* also serve to support these wedges. The smaller ends of the wedges *a a* are towards the front of the carriage, and their inclined sides work against corresponding inclines on the projections *d¹*, so that as the carriage moves forward it clears itself from them. The hinder end of each wedge, *a*, is connected, by a link, *f*, with a spring, *e*, the other ends of the springs *e e* being attached, at *d² d²*, to the forward part of the carriage or framing *d*. Thus, when the carriage is caused to move forward, the wedges *a a* and *b b* will be drawn forward also by the springs, each spring tending to draw its wedges into the spaces between the sides of the rail *c c*, and the inclines formed on the projections *d¹ d¹* of the framing *d* of the carriage. By these means the carriage will be firmly secured to the rails or tramway, so as to prevent lateral motion.

The wedges *a a*, which are at the back end of the carriage, are, in the arrangement shown in the drawing, connected by telescopic rods, *a' b'*; with other similar wedges, *b b*, at the front of the carriage, there being springs, *b² b²*, enclosed within the tubular parts of the rods *a' b'*, which press forward the wedges *b b* towards the front of the carriage. In place of the arrangement above described, other arrangements might be employed for acting on the wedges *a a* and *b b*, so as to press them forward towards the front end of the carriage.

Figures 2, 3, 4, and 5 show the picks or cutting-tools, together with clearers used in combination therewith.

Figure 2 shows a plan.

Figure 3, an elevation.

Figure 4, a section taken at the line *B B* in fig. 2; and

Figure 5, a section taken at the line A A in fig. 2. In this section the picks *a* are the picks or cutting-tools, and *b* are the clearers. The picks *a* are bolted or otherwise secured to the bed, *c*, which can slide to and fro between suitable guides above the top of a frame, *d*, which is fixed above the cylinder *e*, employed for giving the to-and-fro motion to the frame *c*, which carries the cutters. The piston-rod *e* of the cylinder *e* is connected, by the nuts *e*², to the back end of the frame *c*. The clearers *b* are formed with stems, which are received in socket-pieces, *b*¹, which lie at the forward ends of grooves, *c*², formed along the top of the bed *c*, and turn on pins, *b*², as shown. Recesses are formed in the socket-pieces *b*¹ in which small pistons or studs, *c*⁴, are carried. These pistons are pressed outwards from the recesses by springs, *b*³, and caused to bear against the sides of the groove *c*². The socket-pieces thus tend to turn into such a position as to keep the points of the clearers away from the points of the cutting-tools. *f*¹ are sliding weights capable of sliding to and fro in the grooves *c*². The forward ends of these sliding weights *f*¹ are formed with inclines, *f*, which work with corresponding inclines at the rear ends of the socket-pieces *b*¹. As the picks or cutting-tools commence to make their forward stroke, the sliding weights will be at the rear ends of the grooves *c*², so that the inclines *f* will not be acting on the inclines at the rear ends of the socket-pieces. The points of the clearers will thus be away from the points of the cutters, but when the cutters have completed their forward stroke, the sliding weights which have been carried forward by the closed ends of the slots will, by their momentum, be carried forward, and the inclines *f*, at their forward end be brought against the inclines at the rear ends of the socket-pieces, and so turn the clearers, and bring their points towards the points of the cutters, and enclose the small coal or mineral cut away by them. The clearers remain in this position during the backward stroke of the cutters, so drawing back the enclosed pieces. At the end of the backward stroke the momentum of the weights *f*¹ carries them to the rear end of the slots *c*², and then the springs *b*³ again move the points of the clearers away from the cutters, so allowing the small coal or mineral to escape, and the clearers remain in this position during the forward stroke. On the under side of the weights *f*¹ are projections, *f*³, which work in slots, *c*³, in the bed *c*, and act as stops to limit the movement of the sliding weights. *c*⁴ are covering-plates covering the socket-pieces *b*¹. These plates carry springs, *f*⁴, which bear against the top of the sliding weights, and prevent them from rebounding, and so moving away from the socket-pieces after striking against them. The force of the springs can be increased or diminished by screws, *f*³. Although I have only described one arrangement of mechanism for giving motion to the clearers, yet I do not confine myself thereto, as other arrangements of mechanism may be employed; but

What I claim, is—

1. The application of wedges to secure or hold the carriage to the rails, substantially as herein described; and
2. I claim the application of clearers or clearing-instruments to the picks or cutting-tools, substantially as herein described.

G. E. DONISTHORPE.
